[57] CLAIM

The ornamental design for a purified water vending structure, as shown and described.

DESCRIPTION

FIG. 1 is an environmental perspective view of a purified water vending structure, showing my new design; FIG. 2 is a front elevational view thereof;

FIG. 3 is a rear view thereof;

FIG. 4 is a left side elevational view thereof;

FIG. 5 is a right side elevational view thereof; and,

FIG. 6 is a top plan view thereof.

The broken line showing of human figures in FIG. 1 and rectangular lighting fixtures in FIGS. 1-5 is for illustrative purposes only and forms no part of the claimed design.

FIG. 1

FIG. 2

FIG. 3

FIG. 4

FIG. 5

FIG. 6
